UNITED STATES PATENT OFFICE.

AXEL UNO STURE DANIELSSON, OF STOCKHOLM, SWEDEN, ASSIGNOR TO AKTIE-BOLAGET ATLAS-DIESEL, OF STOCKHOLM, SWEDEN.

COMPRESSED-AIR STARTING AND REVERSING MEANS.

Application filed November 23, 1925, Serial No. 70,980, and in Sweden December 1, 1924.

This invention relates to a mechanism in internal combustion engines the main object of which is to reverse the rotary direction of the same by means of compressed air but which may be used also for the starting of the engine. The invention may be applied to engines provided with ignition chamber as well as to engines of Diesel type. According to the invention a cam or the like, which controls the fuel pump or any other member, which effects the feeding of the fuel into the combustion chamber of the engine and also controls the inlet valve for the compressed air, is shiftable into two different positions relatively to the crank of the engine for movement forwards and backwards respectively. In the transmission between the said cam and the inlet valve for the compressed air a hit- and miss device is provided, so that the said valve is acted upon by the cam only while the engine runs slowly. The said hit- and miss device is so arranged, that it remains inactive, while the engine runs at its normal velocity. During the reversing of the rotary direction of the engine the supply of fuel is interrupted, which, when a fuel pump is used, is effected preferably by the suction valve of the pump being held in open position. The opening of the suction valve and the retaining of same in open position is effected by a conveyor, which is rotated by the cam shaft by friction and by means of a suitable motion transmitting device opens the suction valve, as the rotary direction of the engine is reversed from forwards to backwards or vice versa. Owing to the fact that in the said manner motions for the feeding of the fuel, the interruption of same and the controlling of the admission valve for compressed air are derived from the cam shaft a single hand lever or the like may be provided for the reversing of the rotary direction of the engine as will be perceived from the following description, the controlling of the engine being thereby considerably facilitated.

In the accompanying drawings a form of the invention applied to an engine driven by liquid fuel according to the system "solid injection" is shown as an example. Fig. 1 shows the reversing mechanism in a side view. Fig. 2 is a plan view of the same. Figs. 3 and 4 show in a side view and in a

longitudinal section the shiftable cam, 55 adapted to operate the fuel pump as well as to actuate the admission valve for the compressed air. Fig. 5 is a side view of the cam shaft. Fig. 6 is a longitudinal section of the conveyer stated above. Fig. 7 shows the fuel-pump and its suction valve on a greater scale. Fig. 8 is a vertical section of the top part of the working cylinder of the engine and shows the valve controlling the pressure air. Fig. 9 is a detail view showing a hit- and miss device locked in inactive position. Fig. 10 shows in a side view an engine arranged in accordance with the invention. A is the working cylinder of the engine and B the flywheel. The reversing mechanism is 70 provided in a casing C and the fuel pump is located in a casing D.

1 is the cam disc operating the fuel pump. The said cam disc is shiftable into two different positions on the shaft 2 rotating the 75 same and acts upon a lever arm 5 by means of its projection 3, said lever arm 5, being pivoted at 4 and forcing the piston or plunger a of the fuel pump inwards against the action of a spring b. The suction valve of 80 the fuel pump is designated by c. As the plunger a is moved outwards by the spring b, fuel is sucked from a supply pipe d, passes through the valve c and a channel e into the cylinder f of the pump. During 85 the inward stroke of the plunger a fuel is forced through a spring actuated delivery valve g and through a pipe g' to a fuel spreading valve h, which may be of any suitable or known construction, and into the 90 combustion chamber i of the working cylinder j of the engine. If the rotary direction of the engine should be reversed for instance from forwards to backwards, the cam disc 1 is shifted on the shaft 2, so that the position 95 of the cam disc with relation to the crank of the engine, while the engine runs backwards, corresponds to the position of the cam disc and the said crank relatively to one another during the running of the engine 100 forwards and the forcing of fuel into the combustion chamber i of the engine is started at the end of the compression stroke of the working piston k.

The said cam 1 is slidable on the shaft 2 and a fork 6 engages a groove 8 provided in the same by means of lateral pins and dies 7. The said fork 6 is fixed to a shaft 10

journalized in the frame of the engine and provided with a hand lever 9. As the said hand lever 9 is shifted, the cam disc 1 is slid on the shaft 2 in the one and the other direction respectively by the fork 6. In the inner side of the disc 1 two longitudinal grooves 15 and 16 are provided, which in the different positions respectively of the cam disc co-operate with a key 17 fixed on the shaft 2. A longitudinal ridge 20, located between the grooves 15 and 16 and bounding the same at their one side, extends unto the right end of the cam disc, Fig. 4, while a ridge 22 extending round the inner side of the cam disc and bounding the grooves 15 and 16 at their opposite sides does not extend to the said end.

While the engine runs in the one direction and the cam disc 1 is rotated in the direction indicated by the arrow, Fig. 3, the key 17 engages the groove 16. For the reversing of the rotary direction of the engine the cam disc 1 is slid by means of the hand lever 9 toward the left, Fig. 4, until the ridge 22 is located outside the left end of the key 17. The engagement of the shaft 2 with the cam disc 1 is thereby interrupted, for which reason the movement of the cam disc 1 is retarded, while the shaft 2 continues in its rotation, until the key 17 strikes the opposite or left hand side of the ridge 20 and again causes the cam disc 1 to rotate with the shaft 2. The cam disc 1 may then be slid toward the right by means of the hand lever 9 or by the action of a spring 9*, Fig. 10, so that the groove 15 engages the key 17 and the cam disc is locked to the shaft. During the said shifting of the cam disc 1, however, the projection 3 has come into a different position peripherically relatively to the shaft 2 or has been shifted through a certain angle toward the left, Fig. 3, corresponding to the angular distance between the grooves 15 and 16, which new position of the cam disc corresponds to the driving of the engine in a direction opposite to the previous direction. If the rotary direction of the engine should be again reversed, the cam disc 1 is again disengaged from the key 17 by means of the hand lever 9, whereupon the key 17 runs idle inside the cam disc, until it strikes the right-hand side of the ridge 20, and the cam disc may be caused to engage the said ridge by means of its groove 16.

23 is a bell crank lever pivoted at 24. One of the arms of the said lever is connected with the lever 5 by means of the link 25. The connection comprises a pin 26 engaging a slot 27 provided in the link 25 and permits in this manner an idle running for the purpose stated below. To the second arm of the lever 23 a tongue 28 having a wedge shaped end is pivotally connected, which co-operates with an oblique surface 30 provided on an arm 32, which is pivoted

at 31, said surface 30 having a notch 29. A spring 33 forces the said arm 32 against a rod 34, Figs. 1 and 10, acting upon a two armed lever 7 actuating a valve *m* provided between a receptacle containing compressed air (not shown) and the working cylinder of the engine. The said valve *m* is held in closed position by a spring *n*. Tongue 28 is acted upon toward the arm 32 by a spring 35, fixed in the bell-crank lever 23. While the hit- and miss device is operative, tongue 28 is moved upwards by the lever arm 5, link 25 and bell crank lever 23 and downwards by a return spring 78 fixed to the lever 23 and the frame of the engine. During the said movement the upper end of the tongue 28 slides on the oblique surface 30 and, as long as the velocity of the engine is slight, the upwardly moved tongue 28 engages the notch 29 and swings the arm 32 upwards, thus opening the valve *m*, so that the engine is driven by the compressed air. As soon as, however, the velocity of the engine has increased and gained substantially its normal amount the lateral momentum imparted to the upwardly moved tongue 28 by the oblique surface 30 swings the tongue 28 outwards toward the left, so that it misses the notch 29 and does not act upon the arm 32. Tongue 28 is then locked in an upper inactive position in the manner stated below and illustrated in Fig. 10.

The first step of the reversing operation consists in interrupting the supply of fuel, which in the present case is effected by opening the suction valve *c* of the fuel pump. the following means are provided for this purpose. On the shaft 2 a sleeve 41 is fixed, provided with a groove, in which a ring 42 can rotate. The said ring 42 is located between one of the bounding flanges of the groove and a ring 44 slidable axially in the groove and forced against the ring 42 by springs 43, which bear against a ring 45, fixed to the sleeve 41 and constituting the second bounding wall of the groove. Ring 44 is caused to rotate with the sleeve 41 by pins 46 fixed in the ring 45 and engaging recesses provided in the ring 44, said pins guiding the spring 43. Owing to the friction between the ring 42 and the flange of the sleeve 41 and the ring 44, the said sleeve 41 tends to carry with itself the ring 42, while the shaft is rotated in the one or the other direction. A T-shaped tooth 47 is provided on the peripherical surface of the ring 42 and adapted to co-operate with a T-shaped tooth 48 on a link 49, which is connected with an arm 50, fixed to a rocking shaft 51. To the said shaft 51 a two-armed lever 52, 53 is fixed. The arms 52 and 53 of the said lever are connected by means of links 54 and 55 respectively with an arm 57, fixed on a shaft 56. The connection between the links 54 and 55 comprises a pin 58 fixed

in the arm 57 and engaging slots 59 and 60 provided in the links 54 and 55 respectively. Shaft 56 is provided with a cam disc *o*, which as the shaft 56 is turned by the arm 57 being 5 swung towards the left, acts upon a slidable pin *p*, which in its turn opens the valve *c* against the action of spring *r*. Tooth 48 is normally situated outside the path of the tooth 47. From a lateral arm 12 on the 10 shaft 10 a link 61 extends upwards through an opening in the link 49 and is provided with helical springs 62 and 63, which act upon opposite sides of the link 49 and bear against flanges 64 on the link 61 and against sleeves 65, slidable on the link 61 and bearing against the link 49.

66 is a pawl, which is pivoted at 67 and acted upon by a spring 68. The object of the said pawl 66 is to engage a tooth 69 provided on the bell crank lever 23 and thus 20 lock the said lever 23 and the tongue 28 in the upper, inactive position, mentioned above and shown in Fig. 9. In the said position the slot 27 permits the lever arm 5 to swing 25 without acting upon the bell crank lever 23. A link 70 connects a mounting 71 fixed on the link 61 with an arm 72 fixed to a rotatable shaft 73. On the said shaft 73 a ratchet wheel 74 is fixed which is provided 30 for instance with eight teeth and is engaged by a spring actuated pawl 75 carried by the arm 72. A star shaped wheel 76 is fixed on the shaft 73 and adapted to act upon a projection 66^x provided on the pawl 66 Fig. 9 35 in order to bring the pawl 66 out of engagement with the tooth 69 and thus to make free the hit- and miss device.

While the engine operates normally, link 49 is held in a raised position, in which the 40 tooth 48 is located outside the path of the tooth 47 and beside the hit- and miss device is held out of operation by the pawl 66 engaging the tooth 69. The cam shaft 2 rotates for instance in the direction indicated 45 by the arrow, Fig. 1, and the projection 3 of the cam disc 1 actuates the piston *a* of the fuel pump of the engine, so that the engine runs in the ordinary manner. As the hand lever 9 is shifted for the reversing of the 50 rotary direction of the engine, link 49 is first lowered, so that the T-shaped tooth 47 engages the T-shaped tooth 48, in the manner shown in Fig. 1, and moves the links 49 and 54 toward the left, during which movement 55 the link 54 shifts the arm 57 and turns the shaft 56 against the action of a spring 77 and thus opens the suction valve *c* of the fuel pump. While the link 54 is moved toward the left pin 58 moves freely in the 60 slot 60 of the link 55. As soon as the suction valve *c* of the fuel pump is opened, the velocity of the engine is reduced. As the hand lever 9 is thus swung, arm 12 and links 61 and 70 move the arm 72 and the pawl 75 65 downwards but not sufficiently for bringing

pawl 75 into engagement with the subsequent tooth of the ratchet wheel 74. As the operator considers, that the velocity of the engine has been so reduced, that the shifting of the cam disc 1 may be effected in the manner 70 stated above without any member being damaged, he swings the hand lever 9 for a further step in the same direction, so that the cam disc is brought out of engagement with the key 17 by means of the fork 6. At the 75 same time link 61 swings the arm 72 downwards for a further distance so that the pawl 72 engages the subsequent tooth of the ratchet wheel 74. As the hand lever 9 is then 80 swung in the opposite direction, the fork 6 brings the cam disc 1 again into engagement with the key 17 but now in such a position, that the cam disc occupies a position adapted for the driving of the engine in opposite direction, as explained above. 85 During the shifting of the hand lever 9 in the direction last mentioned the arm 72 together with the pawl 75 is moved upwards, so that the pawl 75 rotates the ratchet wheel 74 and thus the star wheel 76, which latter 90 acting upon the lower arm of the pawl 66 disengages the said pawl, so that the hit- and miss device is rendered free during the last part of the shifting of the hand lever 9. As long as the engine runs at a sufficiently 95 great velocity the tongue 28, moved by the lever 5 through the motion transmitting device 27; 23 and against the action of a spring 78, effects some idle strokes, so that the tongue 28 does not act upon the arm 32. 100 Owing to the fact, however, that the supply of fuel to the working cylinder *j* of the engine has been interrupted, the velocity of the engine has been reduced, as stated above, and as soon as the said velocity has been sufficiently 105 reduced either before or after the disengaging of the pawl 66, the tongue 28 will engage the notch 29 of the arm 32, so that the hit- and miss device during each revolution of the engine opens the air valve 110 *m*. Owing to the shifting of the cam disc 1 thus described, the air valve *m* will be held in open position during the last part of the compression stroke of the piston of the engine, for which reason the air at first exerts 115 a checking action during one or more revolutions of the engine shaft, until the inertia of the fly-wheel is not able to rotate the crank past its inner dead centre, for which reason the engine turns back and the compressed air then imparts impulses to the engine driving the same in the new rotary direction. After the rotary direction of the engine has been reversed, ring 42 is rotated 120 by the shaft 2 in the opposite direction, so that the T-shaped tooth 47 is disengaged from the T-shaped tooth 48. Spring 77 now 125 swings the arm 57 toward the right, so that the suction valve *c* of the fuel pump again operates. As the velocity of the engine has 130

been sufficiently increased, tongue 28 effects idle strokes, as well understood from the above description and, owing to the fact that the fuel pump now operates, the engine 5 is again normally driven by fuel fed into the combustion chamber *i* of the engine. As perceived from the above description no fuel will be fed into the said chamber at an 10 improper moment. The tension of the spring 78 is so adapted, that, after the engine has gained substantially normal velocity, the inertia of the lever 23 and the tongue 24, while moving upwards, is able to overcome the tension of the spring 78, so 15 that the tongue 28 moves through a distance which is greater than the distance through which the lever 5 moves the same, the said addition of movement being rendered possible by the slot 27 of the link 25. During 20 the said extended upwards movement of the tongue 28, pawl 66 engages the tooth 69 of the bell crank lever 23 and locks the tongue in its upper position. Tongue 28 and arm 23 then remain in their position of rest, in 25 which the pin 26 slides freely in the slot 27. At the subsequent reversing of the engine pawl 66 is disengaged in the manner stated above. As the link 49 is then lowered the opposite or right end of the T-shaped tooth 29 47 of the ring 42, Fig. 1, engages the left end of the T-shaped tooth 48, so that the link 49 is moved toward the right and by means of the motion transmitting device 52, 51, 53 moves the link 55 toward the left, so that 30 also in this case the arm 57 is swung toward the left and the suction valve *c* of the fuel pump is opened. Owing to the T-shape of the teeth 47 and 48 the link 49 is retained in a reliable manner in its shifted position 35 and keeps the suction valve *c* in its open position, until the rotary motion of the engine has been reversed and consequently ring 40 42 is rotated in the opposite direction and the tooth 47 is disengaged from the tooth 48. As the link 49 is forced downwards, tooth 48 bears against the peripheral surfaces of the sleeve 41 and the ring 44, so 45 that at the shifting of the hand lever for the shifting of the can disc 1, spring 62 is somewhat compressed. As the link 61 is moved upwards at the shifting of the hand lever 9 in the opposite direction, also spring 50 63 is somewhat compressed while tooth 47 still engages the tooth 48 so that the spring 55 63 will swing the link 49 upwards, as soon as the tooth 47 is disengaged from the tooth 48.

As perceived from the above description all functions, necessary for the reversing of 60 the rotary direction of the engine are effected by shifting the hand lever 9. The running of the engine is thereby rendered especially simple. The air necessary for the reversing of the engine may be gained in 65 the usual manner by means of a disengage-

able compressor driven by the engine and an air receptacle. Instead of air any other suitable, compressed gas may be used.

The described and shown means may, evidently, be used also for the starting of the 70 engine in either direction by means of compressed air.

Owing to the fact that the bearing surface (30) for the tongue of the hit- and miss device is provided on the member (arm 75 32), which co-operates with the tongue and is shifted by the same, the said surface may be definitely adapted for the proper co-operation of the members, and no adjusting device is necessary, as, on the other hand, is the case at hit- and miss devices hitherto used, the tongue of which slides on a special plane separated from the actuated member.

The invention may be modified in many respects without exceeding the limits of the 85 same.

I claim:

1. In a device for starting internal combustion engines as well as reversing the rotary direction of the same by means of a 90 compressed medium the combination of a pump for feeding fuel into the working cylinder of the engine, a valve, controlling the compressed medium, means for interrupting the function of the said pump, and a rotating cam, adapted to actuate the said pump and, after the interruption of its function, also the said valve, and means for shifting the said cam into two different angular positions with relation to the crank of the motor shaft whereby driving medium is admitted into the working cylinder at the 95 position of the piston at the one and the other side respectively of the dead center for movement forwards and backwards respectively.

2. In a device for starting internal combustion engines as well as reversing the rotary direction of the same by means of a 100 compressed medium the combination of a pump for feeding fuel into the working cylinder of the engine, a valve controlling the compressed medium, means for interrupting the function of the said pump, a 105 rotating shaft, a cam provided on the said shaft and adapted to actuate the said pump and, after the interruption of the function of the pump also the said valve, two axial grooves provided in the cam laterally of one another, an abutment provided on the cam between said grooves and a key on said shaft adapted upon relative movement between the shaft and cam peripherally to strike said 110 abutment and then be brought into engagement with the adjacent groove, the positions of the grooves and the angular position of the cam with relation to the crank of the motor shaft determined by the same being 115 so adapted that driving medium is admitted into the working cylinder at the position of 120 125 130

130

said piston at the one and the other side respectively of the dead center for movement forwards and backwards respectively.

3. In a device for starting internal combustion engines as well as reversing the rotary direction of the same by means of a compressed medium, the combination of a pump for feeding fuel into the working cylinder of the engine, a valve controlling the compressed medium, means for interrupting the function of the said pump, a rotating cam, adapted to actuate the said pump and after the interruption of the function of the pump, also the said valve and to be shifted into two different angular positions with relation to the crank of the motor shaft for starting and movement forwards and backwards respectively, and motion transmitting means between the said cam and the said valve comprising a hit- and miss device including a movable member, a swingable tongue, a carrier for the tongue imparting a reciprocating movement thereto, said tongue cooperating with said movable member, and a return spring for said carrier, the tension of the said spring being so adapted that, when the engine, after the starting or after the reversing of the same, rotates at substantially normal velocity, the inertia of the tongue and its carrying member overcomes the tension of the spring, so that the tongue moves through a greater stroke, and a catching device locking the tongue after having been thus moved.

35 4. In a device for starting internal combustion engines as well as reversing the rotary direction of the same by means of a compressed medium the combination of a pump for feeding fuel into the working cylinder of the engine, a valve controlling the compressed air, a rotating cam, adapted to actuate the said pump and, after the interruption of the function of the pump, also the said valve and to be shifted into two different angular positions with relation to the crank of the motor shaft for starting and movement forwards and backwards respec-

tively, a rotatable catching member, means for rotating the same by friction, a link, and means for bringing the said link into engagement with the said catching member, so that the link is moved longitudinally, and means whereby the said link, when thus moved, opens the suction valve of the said fuel pump, so that the feeding of fuel is interrupted, until the rotary direction of the engine has been reversed.

5. Starting and reversing device as stated in claim 4, characterized by the catching member and the link being each provided with a T-shaped tooth, means for bringing the link with its tooth into the path of the tooth of the catching member, so that the tooth of the conveyer member engages the tooth of the link and retains the link and the suction valve of the pump in open position, until the rotary direction of the engine and the catching member has been reversed.

6. Starting and reversing device as stated in claim 4, characterized by the catching member and the link being each provided with a T-shaped tooth, means for bringing the link with its tooth into the path of the tooth of the catching member, so that the tooth of the catching member engages the tooth of the link and retains the link, until the rotary direction of the engine and the catching member has been reversed, said link being connected with a two-armed lever and the arms of the said lever connected with a member actuating the suction valve of the pump, an idle motion being provided between the arms of said lever and the suction valve actuating member as the one or the other arm is operative, so that the suction valve is opened at the actuation of the said link in the one and the other direction.

7. In a starting and reversing device as stated in claim 3 the provision of a member adapted to disengage the catching member of the hit- and miss device, and means actuating the said disengaging member at the shifting of the cam.

AXEL UNO STURE DANIELSSON.
